UNITED STATES PATENT OFFICE.

ROBERT DOUGLAS CROW, OF HENDERSON, TEXAS.

COTTON-COMPRESS.

SPECIFICATION forming part of Letters Patent No. 730,881, dated June 16, 1903.

Application filed August 28, 1902. Serial No. 121,309. (No model.)

To all whom it may concern:

Be it known that I, ROBERT DOUGLAS CROW, of Henderson, Rusk county, Texas, have invented certain new and useful Improvements in Cotton-Compresses, of which the following is a full, clear, and exact description.

My invention relates to improvements in that class of cotton-compresses which I use for condensing plantation-bales, so as to reduce their bulk and density.

For many reasons, chiefly for the saving in freight and for convenience in handling, it is desirable to condense "plantation-bales," so called, of cotton, and it is now quite a common practice; but these high-pressure compressors as a rule work rather slowly; and the object of my invention is to produce a compress which will make a condensed bale of the regulation shape and which can be operated faster than the common form of compress.

Other objects of my invention are to make a compress which is very powerful, which is perfectly simple, which can be easily operated, which is little likely to need repairs, and in which the parts are easily accessible.

To these ends my invention consists of certain features of construction and combinations of parts, which will be hereinafter described and claimed.

Reference is to be had to the accompanying drawings, forming part of this specification, in which similar figures of reference refer to similar parts throughout the several views.

Figure 1 is a side elevation of my improved compress. Fig. 2 is a sectional elevation on the line 2 2 of Fig. 1. Fig. 3 is a detail sectional elevation showing a slightly-modified form of side door and operating means therefor. Fig. 4 is a detail sectional view of the exhaust parts of the main cylinder and a means for regulating the exhaust. Fig. 5 is a detail perspective view of the ported flange of the exhaust. Fig. 6 is a detail sectional view of the form of joint used in the steam connections of the main cylinder. Fig. 7 is a cross-section on the line 7 7 of Fig. 6. Fig. 8 is a perspective view of the packing-ring used in the steam-joint, and Fig. 9 is a broken perspective view of a means for counterbalancing side gates or doors.

The compress has a suitable frame 10 and can be in any approved form; but it is shown

as comprising, essentially, four posts which merge into the column 11, which in turn carries the cross-beam 12 at the top; but obviously the form of frame is not material. The framework is mounted on a suitable foundation 13, and the lower part of the frame carries the platens 14 and 15, the former moving vertically, as hereinafter described, and the latter being stationary. The working platforms 16 are arranged on opposite sides of the platen 14 and on the foundation 13 at a height to enable the workmen to operate conveniently when the platen 14 has risen and compressed the bale, it being understood that the ties are applied exactly as usual in such cases.

In making these condensed bales it is desirable to first narrow the bale, which changes its shape without condensing it, and then bring the pressure to bear on it vertically, so as to condense it to the necessary extent. To this end I use inwardly-swinging side gates or plates 17, which are for convenience fulcrumed at the top, the plates 17 forming integral parts of the outwardly-extending levers 18, so that the whole lever is in the form of a bell-crank, and it is stiffened by the strengthening-ribs 19. Each lever or plate 17 is fulcrumed on a cross-rod 20, which is carried in a sliding head 21, (see Figs. 1 and 2,) which head moves up and down in a recess in part 11 of the frame, and each head 21 is carried by the piston-rod 22 of one of the cylinders 23, which cylinders are the ordinary steam-cylinders and have pistons operated by steam or other pressure fluid, the cylinders having inlets and exhaust at each end. I have not shown in detail the construction of the cylinders and their feed and exhaust pipes, for the reason that this structure is common and is not claimed by me, while, on the other hand, I do not limit myself to the use of any particular type of cylinder. Each cylinder 23 has suitable inlet and exhaust pipes 24 and 25, controlled by the valves 26, and the valves are operated by the lever 27, (see Fig. 1,) which is fulcrumed, as at 28, and connects by the rod 29 with a handle-lever 30, the latter being fulcrumed on the frame 10 within easy reach of one of the working platforms 16. The outer end of each lever 18 connects with a piston-rod 31, which is worked

by a piston in the cylinder 32, and the piston-rod is encircled by a spring 33, which acts as a cushion to prevent shock when the pressure fluid is exhausted. The cylinder 32 has feed and exhaust pipes 35, substantially like those of the cylinders 23, and the valves are controlled by a tilting lever 35^a, which is fulcrumed, as shown at 36, and has operating-rods 37.

10 I wish it clearly understood that I have simply generally illustrated common forms of cylinders 23 and 32 and that other types can be substituted. The cylinders 32 are pivotally supported at the top, as shown at 34, as 15 they must of necessity oscillate in operating the levers 18. The cylinders 32 are used for forcing down the outer ends of the levers 18, and so swinging in the pressure-plates 17, and while the pressure fluid in the cylinders 20 would doubtless hold the plates in a compressed position, still, if desired, latches 38 may be used, these being arranged at the 25 free edges of the plates 17 (see Fig. 2) so as to engage catches 39, which are secured to certain rigid parts of the foundation. The catches and latches 39 and 38 hold the plates in place until the bales are vertically condensed.

30 In practice I prefer to counterbalance the side gates 17, so that they will be normally held up without having to maintain pressure in the cylinders 32. Many ways can be devised for counterbalancing the gates, and in Fig. 9 I have shown a simple method. Here 35 the outer end of the lever 18 is connected by a rod 74 with a tilting arm 75, which is fulcrumed on a shaft 76, and the latter supported in a bracket 77, which can be located at any convenient place on the frame, and 40 obviously the shaft 76 can be arranged to support the arm 75 for both gates. The short end of the arm 75 carries a weight 78, which balances the lever-gates 17 18, and so the gates will normally swing out to receive a 45 bale.

To remove the pressure from the piston-rods 22, which carry down the heads 21 and the fulcrums of the plates 18, the rods 20 are provided with pinions 40, which engage with fixed racks 41 on the part 11 of the frame. Instead of this precise steadyng means the arrangement shown in Fig. 3 and hereinafter described can be used for steadyng the compression-plates and for forcing the same inward.

50 The platen 14 is secured to a head-block 42 and may, if desired, be integral therewith, though it is preferably detachable, and the head 42 is split on the under side, as shown 55 clearly in Fig. 2, to receive the levers 43, which are curved outward and downward and have their inner ends formed into toothed meshing segmental parts 45, the levers being fulcrumed in the head-block 42, as shown at 60 44, and so when the levers are at their outer ends moved downward and inward the engaging parts acting on the head 42 will move

the latter upward, thus carrying with it the platen 44. The outer ends of the levers 43 connect with suspending-links 46, which are 70 arranged in pairs on opposite sides of the main frame, the links being hung at the upper ends by the pivots 47 and connecting at their lower ends with the pins 48, which pivotally connect the links with the levers 43 and 75 also with the cylinder 49 and its piston-rod 50, respectively. The cylinder 49 is the main compression-cylinder and is hung so as to swing when the pressure is applied, and it will be noticed that the leverage system just 80 described has a toggle effect, so that the first movement of the levers 43 is comparatively rapid and not so powerful; but as the requirement for more power on the bale increases the outer ends of the levers 43 are moved downward, and so at the final moment enormous 85 pressure is brought to bear on the block 42 and platen 14.

It is necessary to provide a swinging connection with the cylinder 49, and in Figs. 4 90 to 7 I have shown a preferred means of making such a connection. The pipe 51, which supplies steam or other pressure fluid to the cylinder 49, connects with the double-ended casing 52, provided at its ends with stuffing 95 boxes 53 and with an internal flange or diaphragm 54, each flange having a notch 55 therein, (see Fig. 7,) and the pipe 56, which is used in making the joint, has near its ends bosses 57, which can be passed through the 100 notches 55, and then by turning the pipe the bosses are brought out of registry with the notches, thus forming a lock, like the well-known bayonet-joint. The pipe 56 is threaded at its outer ends and in the center is provided with ports 56^a for the passage of the 105 pressure fluid. The packing-ring 58, which is used in the stuffing-boxes 53, is provided with an opening 59 to permit the passage of the bosses 57, and after the pipe 56 is in place 110 the opening 59 can be closed by the plug 60, which has end-tongues 61 fitting in corresponding notches in the ends of the split ring 58. The ends of the pipe 56 connect by the ordinary elbow-couplings 62 with pipes 63, 115 which thus form a yoke or stirrup, and they connect at their lower ends through a second joint 64, like that already described, with the pipe 65, which supplies the pressure fluid.

It is necessary to provide a quick exhaust 120 for the cylinder 49 and yet to check the exhaust at the last moment, so that a cushion will be formed for the piston or the cylinder, as this will be under pressure from the weight of the parts 42, 43, and 46. To this end the 125 piston 66 (see Fig. 4) carries near its periphery and on its outer side the flange 67, which fits in the cup 68 at the end of the cylinder 49, and the flange 67 is provided with a port 70, registering with the main exhaust-port 130 69 and of about the same size as the port, while below or near the outer edge of the flange 67 are small perforations 71, the combined area of which is less than the port 69.

It will thus be seen that as the cylinder 49 exhausts the piston 66 will at first be well within the cylinder, so that the exhaust is uninterrupted; but just before the limit of the stroke 5 the perforated flange 67 partially closes the port 69, thereby checking the exhaust, and finally as the end of the stroke is reached the port 70 registers with the port 69, and the exhaust is therefore wide open in order that 10 it may be fully completed.

In Fig. 3 I have shown a slight modification of the means for working the compression plates or gates 17. As here shown, the cylinders 32^a and 23^a, like the cylinders 32 and 23, 15 already described, are pivoted at their upper ends, as shown at 34 and 72, and the pinions 40 move downward on the outer parts of the racks 41^a and upward on the inner parts of the said racks. These racks are formed in 20 brackets 73, which are fixed on the part 11 of the main frame, or these racks may be made integral with the frame. As illustrated in 25 this figure, the lever 18 is also shown at a less acute angle to the plate 17, and so the cylinder 32^a is pivoted near the center of the main frame instead of to the outer end of the cross-beam 12. In this form of the device catches 39^a are made to form a part of the head-block 42, although they may be rigidly 30 attached, if preferred, and so when the platen 14 moves upward after the gates 17 are closed, as shown by dotted lines in Fig. 3, the platen will carry the gates up with it, thus bringing them into position for use and moving the 35 gates independently of their operating-cylinders. By reference to Fig. 3 it will be seen that the combined pressure from the cylinders 23^a and 32^a will force the gear 40 to the inner portion of the rack 41^a when the gear 40 has reached the limit of its downstroke, and 40 then on the upstroke of the gear it will naturally follow the inner portion of the rack.

In operation the bale to be condensed is wheeled in from the platforms 16 and placed 45 on the platen 14, as in Fig. 1. The pressure fluid is turned onto the cylinders 23, so as to force the inner ends of the levers 18 downward to the position shown in the right end of Fig. 2, and the cylinders 32 are then supplied with the pressure fluid, so as to move 50 down the outer ends of the levers 18, and thus the plates 17 are forced inward and the shape of the bale is changed, making it narrower and higher, after which the pressure is 55 turned into the cylinder 49 and the levers 43 are actuated as described, thereby forcing up the platen 14 and pressing the bale into its condensed shape. It will be seen that all this 60 can be quickly done and that the machinery I use for doing it is of a very simple nature.

Having thus described my invention, what I claim as new, and desire to secure by Letters Patent, is—

1. A compress of the kind described comprising opposed platens movable back and forth in relation to each other, a pair of compression-levers hinged on each of the oppo-

site edges of one of the platens, the said levers having their inner parts formed into compression-plates to engage a bale between the 70 platens, and mechanism for actuating the said levers.

2. A compress of the kind described comprising opposed platens movable back and forth in relation to each other, and a pair of 75 swinging pressure-levers hung near each of the opposed edges of one of the platens, the inner ends of each pair of levers being formed into pressure-plates to engage a bale arranged between two platens. 80

3. A compress comprising opposed platens movable back and forth in relation to each other, a pair of compression-levers hinged opposite the said edges of one platen, the said levers having their inner ends merging in 85 plates to engage a bale arranged between the platens, and locking devices to fasten the free edges of the plates when said plates are swung to their innermost position.

4. The compress comprising opposed platens movable back and forth in relation to each other, a pair of swinging levers arranged opposite each of the side edges of one platen, said levers having their inner ends merging in pressure-plates, swinging at right angles 95 to the back of the platens, and cylinder-and-piston mechanism for moving each end of both levers. 90

5. In a compress, the combination with the platens of the swinging levers arranged near 100 opposite edges of one platen and carrying inwardly-swinging pressure-plates, means for raising and lowering both ends of the levers and pinions and racks for steadyng the fulcrums of the levers. 105

6. In a compress having opposed platens, the platen-actuating mechanism comprising opposed levers carrying the platen and having their inner ends geared together, a movable piston having one end pivoted to one lever and its piston-rod pivoted to the opposed lever, and swinging links suitably supported and connected respectively to the cylinder and lever and to the piston-rod and lever. 110

7. In a compress having opposed platens, 115 the combination with such platens of swinging gates hinged on opposite sides of the platens, a lever mechanism for actuating the gates, and a counterbalance to hold the gates normally open. 120

8. In an apparatus of the kind described, the combination with the opposed platens movable back and forth in relation to each other, of the inwardly-swinging gates pivoted near the side edges of one platen, means 125 for exerting pressure inward upon the gates, and means for moving the gates in the direction parallel with the direction of the movement of the platens by the advance of one of the platens. 130

9. In a compress having opposed platens, the platen-actuating mechanism, comprising opposed levers having their inner ends geared together and arranged to carry a platen, and

a piston-and-cylinder mechanism for swinging the outer ends of the levers inward and downward.

10. In a compress having opposed platens, the platen-actuating mechanism comprising a pair of opposed levers geared together and having their inner ends connected to and directly supporting a platen, a cylinder and piston, one end of the cylinder being pivotally connected to and supported by one lever and the piston-rod of the cylinder being pivotally connected to and supported by the second lever.

11. In a compress, the combination with

the main cylinder having an exhaust-port, of the piston head and rod in the cylinder, and the flange carried by a piston-head, the said flange having perforations to register with the exhaust-port of the cylinder, and a main port to register with the said cylinder exhaust-port.

In testimony whereof I have hereunto set my hand in the presence of two subscribing witnesses.

ROBERT DOUGLAS CROW.
